UNITED STATES PATENT OFFICE.

CLIFFORD E. JOHNSTON, OF ST. LOUIS, MISSOURI, ASSIGNOR OF ONE-HALF TO CHARLES T. EDWARDS, OF ST. LOUIS, MISSOURI.

DESIGN FOR A STATUETTE OR SIMILAR ARTICLE.

55,795.

Specification for Design.

Patented July 13, 1920.

Application filed February 16, 1920. Serial No. 359,186. Term of patent 7 years.

To all whom it may concern:

Be it known that I, CLIFFORD E. JOHNSTON, a citizen of the United States, residing at No. 5316 Odell avenue, in the city of St. Louis, State of Missouri, have invented a new, original, and ornamental Design for a Statuette or Similar Article, of which the following is a specification, reference being had to the accompanying drawing, forming part thereof.

I claim:

The new, original and ornamental design for a statuette or similar article, as shown.

CLIFFORD E. JOHNSTON.
